6 Claims. (Cl. 18—17)

ABSTRACT OF THE DISCLOSURE

A single-level press for the hot-pressing of sheet material, the combination which includes an elongated, vertically fixed, generally horizontal flat press bed, a vertically displaceable generally flat press head extending parallel to and disposed above the bed, a plurality of vertically extending support frames rigidly connected with the head and spaced about the periphery of the bed while vertically bridging them, the frames being displaceable with the head in vertical direction with respect to the bed, and a plurality of fluid-responsive piston-and-cylinder units spaced along the periphery of the bed and acting respectively upon the support frames for vertically displacing the head with respect to the bed.

Our present invention relates to single-stage platen-type presses particularly suitable for the compression of sheet materials, e.g. the compaction of fibrous masses into sheet or plates with or without a binding medium.

In two commonly assigned copending applications, Ser. Nos. 192,038 (now abandoned) and 192,040 now Patent No. 3,241,189, filed May 1, 1962 by Eugen Siempelkamp, one of the present joint inventors, there are described various heated-platen structures of particular advantage in the production of fiberboard and the like. The term fiberboard is used herein to describe the production of all types of pressed sheet material and board for structural, insulating and decorative purposes as well as for a rapidly increasing number of other uses. In general, a mass of cellulosic fibers, e.g. comminuted or steam-expanded wood fibers and the like, are compressed concurrently with heating to form coherent sheets. A binder, for example a phenol-formaldehyde resin, can be admixed with the fibrous mass or comminution can be carried out in such manner that the residual natural thermoplastic resins and lignin of the fiber are sufficient to bond them together at the elevated temperature of the press. It is possible to make use of multi-platen presses for the simultaneous compaction of a number of sheets in this manner, although it is often more convenient to employ single-level presses consisting principally of a bed member (lower platen) and a head member (upper platen) relatively displaceable in the vertical direction. In the commonly assigned copending application Ser. No. 458,228 entitled "Method of and Apparatus for the Production of Pressed Board", filed May 24, 1965, there is described a system for the high rate and substantially continuous manufacture of such pressed board having a single-level press which is provided with heated platens or press members.

For the most part, single-level presses having unitary (i.e. one-piece) bed and head members have hitherto been provided with means for intensively heating the upper or head member of the press and with hydraulic means on the head member for exerting downward pressure upon the latter to compact the sheet material. This construction is disadvantageous in that it is both expensive and prone to disorder because of the elevated temperatures present in the region of the hydraulic mechanism. It is important in presses of this type, moreover, to provide means for equalizing the temperature of the head member

2

since otherwise the latter would tend to warp or distort. This will be apparent from the fact that, when the press is employed for the production of fiber board from wood chips and the like, temperatures up to and in excess of 260° C., are attained.

It is, therefore, the principal object of the present invention to provide an improved single-level press for the production of coherent sheet material in which the disadvantageous effects of elevated temperature are held at a minimum.

Another object of our invention is to provide a press construction which will permit relatively long platen presses to be assembled with a minimum of different parts in accordance with building-block or module techniques.

Still another object of the present invention is to provide a press installation of relatively simple construction, with a minimum of parts and without the need for expensive mounting of the press members.

These objects and others which will become herein-after apparent, have been attained in accordance with our present invention in a single-level press for the hot pressing of sheet material (generally fibrous layers to be formed into coherent sheets but also for the shaping of synthetic-resin, rubber bodies and the like) in which a generally horizontal flat bed member or lower platen is fixed with respect to vertical movement and is juxtaposed with a unitary vertically displaceable generally flat head member or upper platen which can be heated, preferably as described in the copending applications Nos. 192,038 and 192,040 mentioned above; in the structure of the present invention, a plurality of fluid-responsive piston-and-cylinder devices are disposed about the periphery of the lower or bed member of the press below the upper or head member and are operatively connected with the latter for vertically displacing same in the press-closing (i.e. downward) and the press-opening (i.e. upward) direction.

Advantageously a plurality of vertically extending support frames are spaced about the periphery of the press members which may have laterally extending lugs received within the openings of these frame members. Each of the piston-and-cylinder devices are assigned to and preferably carried by a respective support frame. The support frames, which bridge the head and bed members and serve to hold them in alignment via their respective lugs, can constitute force-transmitting means connecting the power devices with the movable head member. Alternatively, the head member is vertically displaceable relatively to the vertically fixed support frames.

According to a preferred system of the present invention, the upper or head member of the press is rigidly connected with the support frames and the latter are vertically displaceable relatively to the lower or bed member while the piston-and-cylinder devices apply the press-closing and press-opening forces to the head member via these frames. Alternatively, the frames can be rigidly connected with the lower platen or bed member or fixed to a common base for the latter while the cylinders of the power devices are received within the portal-like openings of the frames and act upon the head member via pistons whose rods can extend through the laterally projecting lugs of the lower platen or bed member. In the latter arrangement, it may also be desirable to mount the piston and cylinder devices, instead of on the support frames, upon the lower press member.

According to a more specific feature of the present invention, the lugs of the lower or bed member and/or lugs of the support frames (if the latter are vertically fixed) project laterally over the shoulders of the press base or foundation; as set forth in the copending application Ser. No. 458,228, mentioned above, the press can be shiftable to permit a relatively continuous deposition

of the material to be compressed at a charging or dispensing station. Thus, a conveyor band advantageously extends through the press and receives the fibrous layer substantially continuously at a location relatively remote or at least spaced from the press. As the press closes upon the belt, the press is entrained therewith in the direction of displacement of the material during the compression step. At the conclusion of this step, the press opens to release the belt and is returned by hydraulic, pneumatic or other mechanical means to its original position while the belt carries the pressed sheets away and shifts another fibrous layer into position between the platens. In a structure of this type, according to the present invention, the laterally projecting lugs of the bed member or a vertically fixed frame are provided with anti-friction means (e.g. rollers) designed to ride along suitable guide means (e.g. rails) alongside the press. The conveyor belt advantageously has an upper pass overlying the bed member and disposed between the press members for joint movement with the press in the closed condition thereof and for independent operation when the press is opened. The structure of the conveyor belt and other aspects of the fiber board plant are illustrated and described in the last-mentioned patent application. The base can, therefore, be formed with a channel designed to receive downwardly extending portions of the support frames and flanked by a pair of shoulders, ridges or abutments carrying the press via the lugs.

According to still another feature of the present invention, a plurality of press units of the character described are aligned in longitudinally contiguous relationship with respective piston-and-cylinder devices at their mutually adjacent ends. The usual support frames for these devices are then replaced by a connecting support frame bridging the two powering devices along each longitudinal side of the installation for insuring joint movement of the contiguous press members. A further powering device can bear simultaneously upon the adjacent ends of the movable press member to insure such synchronism. Press structures of this type are characterized by some very apparent and surprising advantages. Thus the press consists essentially of four different structural elements, namely the upper and lower press members, the substantially identical support frames, a plurality of which is disposed along each longitudinal side of the press members, and substantially identical powering devices used in conjunction with the frames. The assembly of a press is thus reduced in complexity as is the cost of the installation. Moreover, the elevated temperatures at and above the upper platen of the press can no longer disrupt operation by damage to the power means. Furthermore, the simplified press construction is amenable to module-type assembly of multiple-unit presses of considerable length.

The above and other objects, features and advantages of the present invention will become more readily apparent from the following description, reference being made to the accompanying drawing in which:

FIG. 1 is a side elevational view of a portion of a single-level press, according to the present invention, with the foundation omitted;

FIG. 2 is a cross-sectional view taken generally along the line II—II of FIG. 1 showing the support shoulders for the press;

FIG. 3 is an elevational view showing how the press of FIG. 1 can be joined to a similar module via the connecting frame;

FIG. 4 is a cross-sectional view taken along the line IV—IV of FIG. 3;

FIG. 5 is a view similar to FIG. 2 illustrating another embodiment of this invention;

FIG. 6 is another cross-sectional view similar to FIG. 2 illustrating a modification of this invention; and

FIG. 7 is a plan view of a portion of the device of FIG. 6.

In FIGS. 1-4 of the drawing, we show a press structure, generally designated 100, which can be combined as shown in FIGS. 3 and 4 with similar structures 200 to yield presses of substantially unlimited length. Each 5 press module comprises a vertically fixed lower platen or bed member 2 whose lugs 2a are received within respective support frame members 1 which can have feet 8 projecting laterally and overlying the shoulders 11 of a base 11' whose channel 11" receives the vertically fixed frame members 1. The latter can be mounted upon the 10 foundation or base 11' via a connecting rail 11a, 11b, on each side of the press or can be shifted therealong as illustrated in FIG. 6, in which case suitable straps or platforms can connect the pairs of frames spaced along 15 the opposite longitudinal edges of the bed member 2. A head member or upper platen 3 overlies the bed member 2 and is substantially coextensive therewith, while having lugs 3a extending into the openings 6 of the portal-shaped frames 1. In this embodiment of the device the 20 power means assigned to each of the frames 1 is constituted by a piston-and-cylinder arrangement 4 whose cylinder 4a is received within a rigid respective frame 1 while its piston rod 4b extends through the lug 2a of the bed member 2 above the cylinders. The piston rods 4b 25 are secured to the lugs 3a via bolts 4c and serve to draw the upper press member 3 downwardly when the cylinder 4a is energized. As can be seen at the left-hand side of FIG. 1, where one of the cylinders 4a is broken away, the piston 4d to which the rod 4b is secured, is displaced 30 downwardly to close the press and apply tension to this connecting rod. In the structure of FIGS. 1 and 2, the frames 1 are vertically fixed and the lugs 2 rest upon these frames via the cylinders 4a. It is, however, also contemplated, in accordance with the present invention, that 35 the frames be affixed to the lower press member 2, which, in turn, is supported on the press.

In FIGS. 3 and 4, therefore, we show an arrangement whereby the platens 2 and 3 of press module are substantially contiguous with the lower and upper press members 2' and 3' of a second module 200 which can be identical in all respects with the press module 100. To facilitate connection of the successive press modules, the frames 1 at the extremities of the platen members 2, 3 and 2', 3' are replaced by a connecting-frame member 1a which bridges the ends of the two press modules and is provided with the power devices 4 and 4' which otherwise are identical with those of FIG. 1. In order to equalize the movement of the upper press member, an auxiliary power device 24 with a shiftable support 7 is employed. The auxiliary piston can control the sets of power devices via a servomechanism 25 responsive to disalignment of platens 3, 3' for restoring their coplanarity; the servomechanism 25 can, if desired, also adjust the auxiliary power means 24. While the frame 1a, when 40 used with the press of FIGS. 1 and 2, will generally be provided with feet 8 and carry the lugs 2a and 2a' of the bed members 2, 2' for the purposes of illustration, the frame 1a is shown to be connected rigidly with the lugs 2a, 2a', while feet 8a and 8a' of these lugs support the 45 bed members upon the shoulders 11 (FIG. 2).

In the arrangement of FIG. 5, the feet 28 of the lugs 22a of the bed plate 22 rest upon the rails 11a and 11b of the foundation shoulders 11 which can, therefore, be identical to those of FIGS. 1 and 2. In this case, however, the press-frame members 21 are vertically displaceable with respect to the bed plate or lower platen 2 and are rigidly connected with the upper platen or head member 23 while the hydraulic piston-and-cylinder devices 24 are mounted upon the bed plate 22 and bear, 50 via their connecting rods 24b, upon the head plate 23. Again pressure is applied by tension upon the connecting rods via the hydraulic cylinders which are used within the copendings of the frames 21. The latter are generally 55 rectangular and are of portal configuration as illustrated in FIG. 1 although they are not provided with feet since 75

they are vertically shiftable. The pistons and rods each lie within the opening of the respective frame and a plurality of such frames are provided along the longitudinal edges of the press structure. Several press modules of this type can be contiguously connected via frames such as that shown at 1a in FIG. 3.

In the embodiment of FIGS. 6 and 7, each press module of a longitudinally extended press installation and/or a single-assembly is horizontally displaceable upon the rails 10 of the shoulders 11 of the press base which define the channel 11". In this system, the frames 31, longitudinally spaced along the upper press member 33 and the lower press member 32 are rigid with the bed member 32 at its reinforced laterally projecting lugs 32a. The piston-and-cylinder devices 34, disposed within the openings of the frames, are rigid with the latter and have piston rods 34b extending through the lugs of the bed plate 32 and connected with the lugs 33a of the head plate 33 as described in connection with FIG. 1. The frames 31 or the bed plate 32 carries a horizontal platform 12 upon which the hydraulic means for the power devices 34 are disposed. Such hydraulic means can include a motor 13 for driving the hydraulic pumps 14 and 15 which supply fluid to the cylinders 34a. Motor 13 can be coupled with the rollers 9 via a chain-and-sprocket transmission for returning the press to its original position after it has been displaced during the compression mode of the press. It will be understood that FIGS. 6 and 7 can also be considered to represent an embodiment in which the frames 31 are vertically displaceable and are rigid with the upper member 33 while the rods 34b bear upon the latter member and do not extend to the lugs 33a. In this case actuation of the fluid-pressure means will draw the press head 33 downwardly via the member 31 and the platform 12 can then be vertically shiftable with the frame member 31.

In either case, however, the heating of the upper and lower members 32 and 33 is carried out by circulation of hot fluid from a reservoir 16' through passages represented at 16'. The fluid in the reservoir 16' of the heating device 16 is preferably electrically heated by resistance heaters immersed in the liquid. It will be understood that the fluid channels within the press platens of this embodiment as well as those of FIGS. 1-5 may be disposed and connected as fully described in the aforementioned copending applications Ser. No. 192,038 and Ser. No. 192,040.

Furthermore, a conveyor belt 15 passes through the press and has its upper and forward pass or stretch disposed above the lower platen 32 for carrying the comminuted material to be pressed between the platens. The lower stretch passes beneath the lowered platen 32 but above the platform 12. This pass may have a conveyor belt of steel as described in the above-identified copending application Ser. No. 458,228 and may, therefore, be incorporated in a manufacturing installation of the character set forth therein. Upon closure of the press the latter is entrained along the rails 10 for the duration of the compression step and, upon opening, is returned in the opposite direction to receive an additional layer of material to be compressed.

The invention described and illustrated is believed to admit of many modifications within the ability of persons skilled in the art, all such modifications being considered within the spirit and scope of the appended claims.

We claim:

1. In a single-level press for the hot-pressing of sheet material the combination which comprises:
an elongated, vertically fixed generally horizontal flat press bed,
a vertically displaceable generally flat press head extending parallel to and disposed above said bed,
a plurality of vertically extending support frames rigidly connected with said head and spaced about the periphery of said bed while vertically bridging said bed and said head, said support frames being displaceable with said head in vertical direction with respect to said bed, and
a plurality of fluid-responsive piston-and-cylinder devices spaced along the periphery of said bed and acting respectively upon said support frames for vertically displacing said head with respect to said bed.
2. The combination defined in claim 1 wherein said bed and said head are generally rectangular in plan view, and a plurality of said support frames with respective ones of said piston-and-cylinder devices positioned therein are disposed along each longitudinal side of said bed and said head.
3. The combination defined in claim 1, further comprising heating means for heating said head said heating means including means forming a plurality of fluid passages in said head, and means disposed on said head member for circulating a heating fluid through said passages.
4. The combination defined in claim 1 wherein said bed is provided with respective laterally extending lugs projecting into the openings of said frames for aligning said bed with said head.
5. The combination defined in claim 4, further comprising an endless band for conveying said sheet material through said press, said band having an upper stretch extending along the upper surface of said bed and a lower stretch passing below said bed.
6. The combination defined in claim 5, further comprising antifriction means disposed laterally outwardly of said frames and carried by the lugs of said bed member for supporting same with freedom of horizontal movement upon a base for said press, said frames being entrained by said bed upon horizontal displacement thereof together with said band.
